UNITED STATES PATENT OFFICE.

ELI BROTHERS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING APPARATUS.

Application filed September 14, 1912, Serial No. 720,380. Renewed May 6, 1918. Serial No. 232,979.

To all whom it may concern:

Be it known that I, ELI BROTHERS, a citizen of the United States, residing at Lynn, in the county of Essex and State of Massachusetts, have invented certain Improvements in Lasting Apparatus, of which the following description, in connection with the accompanying drawings, is a specification, like reference characters on the drawings indicating like parts in the several figures.

This invention relates to the manufacture of boots and shoes and among its objects are to facilitate the shaping of an upper to its last and the permanent fastening of the upper to the innersole or the sole, and to protect the upper from injury or soiling during the shoe making operations.

An important feature of the invention consists in novel apparatus for use in working an upper into lasted position on a last. The construction herein shown as an illustrative embodiment of the invention comprises a device constructed to extend about substantially the entire periphery of a shoe in conforming relation to the contour of the lateral surface of the shoe lengthwise of the bottom edge about the forepart and while abutting against the shoe at the rear of the heel portion to be forced in a direction to wipe the upper at the forepart over the lateral surface of the last toward the bottom edge of the shoe. By use of the device in this manner the upper is wiped into lasted position with the margin of the upper standing substantially at right angles to the plane of the sole of the shoe. Preferably the device is made of resilient material to cause it to conform to slight irregularities in the shapes of different shoes while presenting normally a contour characteristic of the shoes of a given size and style. The device herein shown is also shaped to conform substantially to the vertical contour of the shoe about the forepart for a considerable distance from the bottom edge of the shoe, this construction serving both to increase the effectiveness of the device in its action upon the upper and also to limit the wiping movement of the device.

In accordance with a further feature, the invention provides novel means for use in holding an upper in lasted position. The construction shown comprises means for

clamping the updrawn upper about the periphery of the forepart of the shoe to the lateral surface of the last and the edge face of the sole, the clamping device being portable to permit it to be carried with the shoe and presented to a machine for securing the upper to the sole. An advantageous characteristic of the illustrative construction, as adapted for use upon some types of shoes such as turn shoes, is that while holding the upper securely in place it leaves a portion of the upper located opposite to the edge of the sole free to be operated upon in the upper and sole securing operation. Preferably, moreover, the device presents an uninterrupted exterior face substantially parallel to the lateral contour of the last adjacent to the shoe bottom adapted to serve as a guide during the presentation of the shoe to a machine for securing the upper to the sole. While this feature of the invention is herein shown as embodied in upper holding means adapted for use initially to work the upper into lasted position in the manner hereinbefore explained, in its broader aspects the invention contemplates the provision of novel means for holding an upper in lasted position irrespective of the particular manner in which the upper may have been tensioned and conformed to the last.

Still another feature of the invention consists in the combination with a last of a shoe embracing member adapted to fit snugly the lateral surface of the shoe while leaving the lower surface exposed, such member serving to protect the upper of the shoe from injury or from being soiled during subsequent manufacturing operations.

By the use of the illustrated embodiment of this invention important advantages are obtained among which may be mentioned economy of time and labor and upper stock as well as the saving of toe fastening material, together with a superior quality of toe lasting because good qualities of the wiper type of bed lasting are secured without the slackening back of the stock which is incident to the withdrawal of machine lasting plates after the application of the temporary fastening means in order to permit the shoe to be presented to the welter.

Other features of the invention, several of which are important and which include cer-

tain details of construction and combinations of parts, will appear from the following description of a preferred construction and will then be pointed out in the claims.
5 The improvement in methods of making shoes which is herein disclosed is claimed in a divisional application Serial No. 100,366, filed on May 27, 1916, upon which Letters Patent No. 1,482,220 were granted on January 29, 1924.

Fig. 1 is a side view of apparatus in which the invention is embodied:

Fig. 2 is a perspective view of the apparatus shown in Fig. 1;

15 Figs. 3 and 4 show modifications.

Fig. 5 shows a section through a shoe lasted by this apparatus and held in lasted condition thereby while being sewed, the shoe in this instance being a turn shoe, and 20 this figure also illustrating how a welt may be secured to the upper and insole of a lasted shoe in the case of a welt shoe.

The apparatus shown in the drawings 25 consists primarily of a toe or a forepart embracing member 2 in the form of a shell which may advantageously be made of spring metal and which is shown as of thin spring metal shaped substantially to the contour of the edge portion of the last with 30 which it is to co-operate, being a snug fit thereto so that as it is forced upwardly on the shoe about the inverted last, Fig. 1, it will wipe the upper stock into lasted position and there maintain it. The member 2 35 is preferably so formed on its inner side that it is concave in vertical cross section and inclined rearwardly at the toe end, said face being shaped to conform substantially to the vertical contour of the toe end of the 40 last. This has two advantages. The shaping action is extended downwardly from the edge of the inverted last when said member is in place so that the upper is clamped to the side face of the last for a substantial 45 distance from the last edge downwardly. Also this shape assists the operator in positioning the end embracing member at the right elevation relatively to the plane of the last bottom to hold the upper most effectively and to facilitate subsequent operations on the shoe embraced by said member.

The embracing member 2 is to be attached 50 to the shoe for maintaining the upper stock in lasted position while the shoe is handled, as for the purpose illustrated in Fig. 5. While various constructions may be employed for attaining this result, I prefer to extend the sides of the member 2 rearwardly as at 3 to, and it may be around, the heel 55 end of the shoe. In Figs. 1 and 2 the ends 3 are connected yieldingly and adjustably by a bolt 4 and springs 5, 5 while in Fig. 3 they are connected yieldingly by a bow 60 spring 6 and in Fig. 4 they are connected 65 adjustably by a stud and eccentric latch 7.

These constructions all have the advantage that no projection above the shoe bottom is presented which would interfere with the operation thereon of such machines as the sewing machine of Fig. 5. The rear end 70 portions 3 are cut away at their bottom edges 8, or are deflected downwards to allow a heel seat lasting and tacking machine to operate upon the side as well as the bottom of that portion of the shoe which includes 75 the heel stiffener.

The embracing member 2 preferably includes portions shaped to lay the upper stock at the shank into the shank curvature of the last in position for sewing as at 80 9 and these shank formers or wipers 9 may or may not be hinged to the member 2 as at 10, Fig. 3.

The embracing member may be applied 85 by hand, as by passing it over the shoe in such manner as to encounter the least resistance and locating its heel end portion in approximately final position in abutting relation to the heel end face of the shoe and then swinging the forward portion upwardly 90 with the fingers while the thumbs rest upon the shoe bottom, whereby the entire forepart and shank of the upper is wiped up at once to the position shown in Fig. 1 and is secured in lasted position as there shown. The 95 upper at and about the toe may be doubled down over the top edge of member 2 while said member is being forced upwardly whereby desired tensioning of the upper 100 may be obtained at whatever places it is 100 needed.

In Figs. 1 and 2 is shown means for effecting the toe lasting movement of the embracing member 2, said means comprising a toggle the upper arm 12 of which is 105 forked to have detachable engagement with lugs 13 on members 2. The lower toggle arm 14 is pivoted to a fixed support such as the rod 15 that is held by binding screw 16 in a last pin 17 with capacity for adjustment 110 to use with shoes and embracing members of different lengths. The toggle has an operating member 18 which is rigid with upper arm 12 and which has a face 19 to engage an abutment on arm 14 by which the 115 toggle is locked when it has been operated to straightened position. These arrangements, taken with the adjustment of the rod 15, provide for raising the embracing member 2 to an approximately uniform vertical 120 relation to the shoe bottom, it being preferable that it should occupy substantially the operative position disclosed in Figs. 1 and 5, in which it partially overlaps the edge 125 face of the sole and maintains the upper in lasted position against said edge face with the margin of the upper standing substantially at right angles to the plane of the sole.

The parts above described constitute with the embracing member 2 a lasting machine 130

of which the lasting means 2 is adapted, while holding upper stock in lasted relation to the last, to be removed with the shoe so as to maintain the upper in lasted condition while the shoe is being presented to another machine, as for example the fastening machine indicated in Fig. 5. The device is effectively retained in position for holding the upper about the forepart through the action of the heel embracing portion assisted by the rearwardly curved toe portion and the inwardly curved shank portions of the device.

In Fig. 4 the embracing member 2 has a portion 20 to press the upper into the low place usually found on the top face of the last between the toe and the instep. In this figure also the member 2 is formed in two sections connected by hinges 21. When the latch 7 has been unfastened the sections of member 2 can be turned to open said member for removal from a shoe after the upper has been fastened, Fig. 5, without wiping the upper down from the edge of the last.

It is contemplated that use will be made of the illustrated apparatus by applying an upper to a last and then applying the embracing member 2, positioning its heel portion substantially as shown and forcing the forward portion upwardly in rubbing contact with the stock to wipe the upper to lasted position, Fig. 1, after which the shoe with the embracing member 2 clamping the stock in lasted position will be removed to a convenient place and subjected to a suitable upper and sole connecting operation, for example as in Fig. 5, or if it be a McKay shoe the upper margin will be laid inwardly over and tacked to the innersole.

It will be evident by reference to the drawings that the member 2 presents an uninterrupted exterior surface which is substantially parallel to the lateral contour of the last lengthwise of the bottom edge of the shoe, this surface being adapted to serve advantageously as a guide in the presentation of the work to a machine for securing the upper to the sole. This smooth surface is entirely free from such irregularities as are presented on the lateral surface of a shoe, as, for example, at the rear edge of the toe tip, and by the use of the device the operation of securing the upper to the sole is consequently facilitated.

It will be apparent furthermore that by the use of this invention the usual time consuming operation of temporarily fastening the upper in lasted position by the use of fasteners inserted in the shoe is entirely eliminated whereby labor is saved; that the slackening back of the stock which results to a greater or less degree upon withdrawal of the lasting means after application of temporary fastenings is avoided so that tighter lasting and permanent fastening are ob-

tained and the appearance of the shoe thereby improved; and that the upper pattern may be cut substantially smaller because it is only needful that it be long enough to permit the permanent fastening as in Fig. 5 or otherwise.

It should be understood that the term "sole" is used herein in its generic sense and except where required by the context imports no limitation as to the specific character of the bottom portion of the shoe to which the upper is to be secured to hold it in lasted position, whether the shoe be a welt shoe or a turn shoe or a shoe of other type.

Having explained the nature of this invention I claim as new and desire to secure by Letters Patent of the United States:

1. Apparatus of the class described comprising a lasting device shaped to embrace the toe of a last and formed in vertical cross section to conform to the vertical contour of the toe end of the last, said device being constructed and arranged for manipulation to wipe the upper stock upwardly about the end and side faces of a shoe toe into lasted relation to said faces and for temporary attachment to said shoe for holding the upper stock in such lasted position while the shoe is being subsequently handled for presentation to an upper and sole connecting machine.

2. Apparatus of the class described comprising a resilient forepart embracing member constructed and arranged to engage the toe of an inverted shoe below the plane of its bottom face and be raised and advanced to wipe the upper stock upwardly along the end and side faces of the forepart of the last to said plane, said member having means to limit its upward movement relatively to the toe of the last and being adapted to remain on the shoe clamping the stock to the edge of the shoe forepart while permitting the shoe to be handled in presentation to an upper and sole connecting machine.

3. Apparatus of the class described comprising a portable forepart embracing member adapted for attachment to a shoe and for turning movement on the shoe to which it is attached for wiping the upper stock into lasted position about the toe and maintaining it in such position while the member remains attached to the shoe, the inner face of said member being inclined rearwardly at the toe to limit its movement in wiping the upper toward lasted position.

4. Apparatus of the class described comprising a resilient forepart embracing member having its rear ends movably connected to clamp said member to the shoe and movable angularly about said ends to wipe the upper stock into lasted position about the toe of a last and clamp it around the edge of the toe, said member having limiting means to engage the shoe and prevent pro-

jection of said member above the edge of the toe.

5. A combined lasting and temporary fastening device comprising a resilient member shaped to embrace and yieldingly clamp the forepart of a shoe and having arms extending to the heel of the shoe, said member having an edge contour corresponding substantially to the curvature of the edge of the 10 forepart of the last and the arms being cut away to present clearance around the heel for heel seat lasting and tacking operations.

6. A combined lasting and temporary fastening device comprising a forepart embracing member having rear arms suitably shaped and yieldingly connected to clamp the heel end of a shoe and maintain the device in upper holding position about the shoe forepart, said arms being cut away at their 20 upper edges to clear the edge of the shoe around the heel seat.

7. A combined lasting and temporary fastening device comprising a forepart embracing member having rear arms shaped 25 and yieldingly connected to clamp the heel end of a shoe and provided with inwardly inclined portions shaped to lay the upper stock at the shank of the shoe into the shank curvature of the last.

8. A combined lasting and temporary fastening device comprising the forepart embracing member 2 having its rear ends 3 suitably shaped and yieldingly connected to clamp the heel end of a shoe and having 35 pivoted shank formers 9, substantially as described.

9. A combined lasting and temporary fastening device comprising a resilient member shaped to embrace the forepart of a shoe and 40 to clamp the shoe yieldingly by its rear ends combined with means having detachable engagement with said device and constructed and arranged relatively to said forepart embracing member to turn it to wipe the upper 45 upwardly about the toe of the last when actuated in one direction and operating to leave the device in upper holding position when actuated in the reverse direction.

10. A combined lasting and temporary fastening device comprising a resilient member shaped to embrace the forepart of a shoe and to clamp the shoe yieldingly by its rear ends combined with a toggle 12, 14 having detachable engagement with the said device 55 for raising the toe end thereof and leaving it raised when the toggle is reversely moved substantially as described, and adjustable to adapt the operation of said device to the size of the shoe.

11. Apparatus of the class described comprising a portable lasting and upper holding device of resilient material, one portion of said device being shaped to embrace the forepart of a shoe and having an 65 upper edge of substantially the same out-

line as the lengthwise curvature of the forepart of the last bottom and other portions of said device comprising arms extending around the heel with their upper edges at a substantial distance below the edge of the 70 heel seat, said device being adapted to have an assembled shoe inserted through it and then to permit relative turning movement of the device and the shoe to cause the device to wipe the upper up the side faces of the 75 shoe forepart to the edge of the shoe bottom and clamp the upper to the last, along the edge of its forepart by the resiliency of the device.

12. Apparatus of the class described comprising a portable lasting device and temporary toe fastener including a forepart embracing member 2 which is made of spring metal and which is shaped substantially to the contour of the edge portion of the last 80 with which it is to co-operate, being a snug fit thereto, and having portions shaped to lay the upper stock into the shank curvature of the last in position for sewing to the shoe sole.

13. The combination with a shoe last, of a shell snugly fitting the lateral surface thereof but leaving the under surface exposed, said shell being cut apart on a vertical line, and means for forcibly drawing toward 95 each other the edges of said cut shell.

14. The combination with a last, of a shell inclosing the sides thereof but leaving the under surface of the last exposed, the heel of said shell being cut apart on a vertical line, said shell having means for forcibly drawing toward each other the edges of the cut shell.

15. The combination with a shoe last, of a shoe embracing member of resilient material 105 which is constructed and arranged to adapt itself at substantially every point of contact to the contour of the last and snugly fitting the lateral surfaces of the last but leaving the under surface exposed, said member being cut apart on a vertical line, and means for forcibly drawing toward each other the edges of said member.

16. The combination with a last, of a resilient shoe embracing member constructed 115 and arranged to adapt itself at substantially every point of contact to the contour of the last, said member inclosing the sides and extending uninterruptedly around the forepart of the last while leaving the under surface of the last exposed, the heel of said member being cut apart on a vertical line, said member having means for forcibly drawing toward each other the edges of its heel portion.

17. Apparatus of the class described comprising a lasting device constructed to wipe an upper over the lateral surface of a last into lasted position by relative movement 120 of said device and the last and to position 130

- the upper with its margin upstanding substantially at right angles to the plane of the sole of the shoe, said device being constructed to embrace the forepart of the shoe 5 and to conform yieldingly to variations in the curve of the lateral surface of the last about the forepart, the device being also portable with the shoe and constructed to hold the upper in said lasted position while 10 the shoe is presented to a machine for securing the upper to the sole.
18. Apparatus of the class described comprising a device constructed to extend about substantially the entire periphery of a shoe 15 on a last and to conform yieldingly about the forepart of the shoe to variations in the curve of the lateral surface of the last lengthwise of its bottom edge, said device being constructed to abut against the rear 20 end face of the shoe and by swinging movement about said face to wipe the upper at the forepart in the direction of the bottom edge of the shoe and then to hold the upper in finally lasted position with the margin 25 of the upper upstanding substantially at right angles to the plane of the shoe bottom.
19. Apparatus of the class described comprising a device constructed to extend about substantially the entire periphery of a shoe 30 and to conform substantially to the contour of the lateral surface of the shoe lengthwise of the bottom edge about the forepart, said device having a portion constructed and arranged to abut against the rear end face of 35 the shoe to resist forward thrust, and means for swinging said device substantially about the rear end portion of the shoe for wiping the upper into lasted position at the forepart of the shoe.
- 40 20. Apparatus of the class described comprising a device constructed to embrace a shoe about the forepart and by movement toward the bottom of the shoe to wipe the upper into lasted position with the margin 45 of the upper upstanding substantially at right angles to the plane of the sole of the shoe, said device being portable with the shoe and constructed to hold the upper in said lasted position, and means for detachably engaging said device and imparting thereto its upper wiping movement.
21. Apparatus of the class described comprising a lasting device constructed to extend about the periphery of the forepart of a shoe and by relative movement between it and the shoe to wipe the upper into lasted position, said device being constructed to hold the upper in lasted position and having an exterior surface substantially parallel to 55 the curve of the lateral surface of the last lengthwise of the bottom edge of the shoe round the forepart to serve as a guide during presentation of the shoe to a machine for securing the upper to a sole.
- 60 22. In apparatus of the class described, a device constructed to extend about the periphery of a shoe at the forepart and to hold the upper in lasted position while the shoe is presented to a machine for securing the upper to the sole of the shoe, said device being so 70 constructed as to leave a portion of the upper located between the planes of the bottom and top faces of the sole free for the operation of said machine thereon.
23. In apparatus of the class described, a device constructed to extend about the periphery of a shoe at the forepart and to hold the upper in lasted position with the margin of the upper upstanding substantially at right angles to the plane of the sole of the shoe, said device having means for positioning it in such relation to the shoe as to present that edge of the device which is adjacent to the bottom of the shoe in a location 75 between the plane of the exposed face of the sole and the top of the shoe.
24. In apparatus of the class described, a device of resilient material constructed to extend about substantially the entire periphery of a lasted shoe and to conform 80 itself substantially to variations in the curve of the lateral surface of the shoe lengthwise of the bottom edge of the shoe about the forepart for holding the upper of the shoe 85 in lasted position.
25. In apparatus of the class described, a portable holding device constructed to effect substantially continuous engagement with the upper of a lasted shoe round the toe exteriorly of the edge of the shoe bottom while 90 leaving the marginal portion of the bottom face of the shoe exposed all round the toe, said device presenting an uninterrupted exterior face substantially parallel to the curve 95 of the last round the toe lengthwise of the bottom edge of the last and affording a surface by which the shoe can be guided in subsequently presenting the shoe to a machine for securing the upper to a sole.
26. In apparatus of the class described, a device constructed to extend about the peripheral surface of the forepart of a lasted shoe to hold the upper in lasted position, said device having a toe end portion constructed to incline rearwardly toward the 100 top of the toe of the shoe and other portions constructed to extend inwardly toward the bottom of the shoe at opposite sides of the shank to assist in positioning the device.
27. In apparatus of the class described, a device constructed to extend about substantially the entire periphery of a lasted shoe to hold the upper in lasted position, said device being constructed to present a bottom edge portions of which are located respectively at different distances from the bottom 105 of the shoe.
28. In an apparatus for lasting shoes, the combination with a last, of means for working an upper over the last and for holding 110
- 115
- 120
- 125
- 130

it in finally lasted position with its margin upstanding substantially at right angles to the plane of the sole of the shoe, said overworking and holding means being constructed to serve as a guide in presenting the work to a machine for securing the lasted upper to the sole.

29. A lasting machine having, in combination, a wiper, and means for operating the wiper to wipe the upper into lasted position with its margin standing at the edge face of the insole substantially at right angles to the plane of the insole.

30. A lasting machine, having, in combination, a wiper, and means for operating the wiper to wipe the upper into lasted position

against the edge face of the insole, substantially as described.

31. A lasting machine, having, in combination, wipers arranged on opposite sides of the shank of the shoe, and means for operating the wipers to wipe the upper into lasted position against the edge face of the insole, substantially as described.

In testimony whereof I have signed my ²⁵ name to this specification in the presence of two subscribing witnesses.
